JOSEPH VOWLES, OF MILFORD, MICHIGAN.

Letters Patent No. 84,029, dated November 10, 1868.

IMPROVEMENT IN CULTIVATORS.

The Schedule referred to in these Letters Patent and making part of the same.

To all whom it may concern:

Be it known that I, JOSEPH VOWLES, of Milford, in the county of Oakland, and State of Michigan, have invented a new and useful Improvement in Cultivators; and I do hereby declare that the following is a full, clear, and exact description of the same, reference being had to the annexed drawings, making part of this specification.

This invention consists—

First, in the construction of the reversible mould-board,

Secondly, in the device by which the tongue is raised or lowered.

Thirdly, in the construction of the lever which is attached to the axle, and in the means for attaching it thereto.

Fourthly, in the general arrangement of the parts of which the cultivator is composed.

Figure 1, sheet 1, is a perspective view of the machine, showing its general arrangement, as well as the device for raising and lowering the same upon its axle, and the reversible mould-board attached to its hangers.

Figure 2, sheet 2, is a sectional side elevation, showing the device for raising the machine, or for lowering the same, so as to give the plows the required adjustment, or to remove them from the earth altogether, so as to facilitate the transportation of the machine from one place to another.

Figure 3 is a rear cross-section, showing the bent axle, the mechanism for raising and lowering the frame and plows or teeth, and a rear-end view of the mould-board, with the means of attaching it to the frame.

Figure 4 is a view of the reversible tooth or plow, showing the manner of attaching the same to its hanger.

Figure 5 is a view of the lever which is attached to the main shaft, for raising or lowering the frame-work of the machine to which the teeth or plows are suspended, by which means the depth of the furrow is regulated, and it also shows the sector, by which said lever is secured in any desired position, and the means of attaching said lever to said shaft.

Figure 6 is a side view of a portion of the tongue, and of the sub-tongue to which it is attached, and it also shows an end view of the wedge or device for raising or lowering the forward end of the tongue, as circumstances may require.

The same letters indicate the same parts in all the figures.

A A are the wheels, which are secured to the axle in the usual manner.

B is the axle, which is constructed as shown clearly in fig. 3 of the drawings, the object being to attach the frame-work of the machine to the straight portion of the axle, within the offsets, so that it may be raised up, as shown in said figure, to such an extent as to permit the machine to be drawn from one place to another without permitting the teeth to come in contact with the earth, or it may be turned down, by

means of the lever C, so as to assume the position shown in fig. 2, and so as to allow the teeth to enter the earth to any required depth.

C is the lever, which is attached to the axle for the purpose above described. Said lever is of peculiar construction, the cavity a in its lever-end being semicircular in form, and having a slight projection cast upon it to enter a recess made in the shaft or axle B, to prevent the possibility of its failing to move the axle when it is moved.

To the lower end of this lever is attached a cap, b, having a cavity in it similar to the one above described, so that when it is placed upon the lever, the two will embrace the axle, and the inner end of the cap will rest upon the lever, whilst their outer ends will be some distance apart, so that as the bolt a is passed through them, and the nut secured down, the two will be permanently attached to the axle.

D is the sector, which is secured to the frame-work of the machine, by the side of the lever, and has a series of holes drilled or cast in it to receive and hold a pin, which is attached to a handle, which is attached to the outer end of the lever C, and is pivoted thereto in such a manner that when held in the position shown in fig. 3, the lever will be retained in its position thereby, but when it is desired to change the position of the lever with reference to the sector, for the purpose of raising or lowering the teeth or plows, the upper end of the handle is pressed inwards, and the pin is thus withdrawn from its seat in the sector, and the lever can be moved to any desired position, when, by releasing the hold upon the handle, a spring, screwed between it and the lever, will return the pin to its position within the sector, and thus the lever will be secured in its new position.

E E E are the timbers composing the frame of the machine, and to which the hangers which carry the teeth or plows are attached. These timbers are of the requisite size to give the strength required, say two and one-half by three and one-half inches, and are held together at their ends or points of contact by bolts and nuts in the usual manner. The rear one of these timbers is considerably longer than the front one, and is for the purpose of fastening thereto the hangers, which carry upon their upper ends handles, by which the machine is guided with reference to the rows of the crop.

F is a sub-tongue or timber, extending from the rear cross-timber E to and some distance beyond the front one, the object being to attach to the projecting portion the adjustable tongue. This sub-tongue also carries one of the hangers K.

G is the tongue of the machine, and it is attached to the sub-tongue in such a manner that its forward end may be raised or lowered, as circumstances may require, independent of the particular position of the frame of the machine.

The device for accomplishing the above-named re-

sult consists of a wedge-shaped piece of metal, having flanges upon its ends, placed between the tongue and the sub-tongue, so that by unscrewing the nut of the bolt which confines the two together, and moving the above-described wedge forward, the outer end of the tongue will be raised, and *vice versa*.

H H are the two rear hangers, which are provided with handles, as above described, and which are attached to the rear cross-beam E, at such a distance apart that the tooth or plow placed thereon shall be nearly or quite in the rear of the wheels, and that the furrows turned therby shall obliterate the track made by such wheel.

I I are braces leading from the hangers H and K to the main frame, for the purpose of supporting said hangers.

K K are hangers, attached to the sides as longitudinal portions of the frame, and they are so arranged as to occupy a position transversely between the two which are attached to the rear beams, and, when furnished with the reversible mould-board M, as shown; and when the other teeth with their hangers are removed, as they may be at any time, they may be used conveniently and advantageously for what is termed "hilling up" the crop.

L L are the teeth or mould-boards, which are bolted to the lower ends of the hangers, as above described, and which are believed to be of novel construction, said novelty consisting in their being cut straight, or nearly so, upon one of their sides, whilst the other is cut in the form of a circle, thus forming, when bent to the proper form, a mould-board, which, when worn out

upon one end, may be readily reversed, by loosening the bolt which secures it to the hanger, and the unworn end be substituted for the worn one.

It will be seen, also, that the above-described mould-boards may readily be changed at any time for the purpose of turning the furrows in opposite directions.

N is the wedge-piece above described, for changing the position of the forward end of the tongue.

Having thus described my invention,

What I claim as new, and desire to secure by Letters Patent, is—

1. The mould-board L, constructed substantially as shown and described.

2. The combination of the mould-board L with a cultivator.

3. The construction of the wedge N, and its arrangement with reference to the tongue of a cultivator, or for any equivalent purpose, substantially as shown and described.

4. The arrangement of the hangers H H with their teeth M M, with reference to the wheels of the machine, substantially as shown and described.

5. The arrangement of the sub-tongue F, frame E, sector D, lever C, hangers H and K, and braces I, substantially as shown and described.

In testimony whereof, I have signed my name to this specification, in the presence of two subscribing witnesses.

JOSEPH VOWLES.

Witnesses:

PHILIP F. WELLS,
DAVID CONNER.
